CLAIM

The ornamental design for a bottle holder, as shown and described.

DESCRIPTION

FIG. 1 is a top, right, front perspective view of the bottle holder, illustrating the novel design.

FIG. 2 is the right side view thereof.

FIG. 3 is the left side view thereof.

FIG. 4 is the front side view thereof.

FIG. 5 is the back side thereof.

FIG. 6 is the top view thereof; and,

FIG. 7 is the bottom view thereof.

The broken lines are shown for the purpose of illustrating parts of the article that form no part of the claim.

1 Claim, 4 Drawing Sheets
